United States Patent Office

Des. 183,801
Patented Oct. 28, 1958

183,801

ANIMATED ROCKING SEAT

Thomas C. Martin, Boston, Mass.

Application June 14, 1957, Serial No. 46,594

Term of patent 14 years

(Cl. D34—15)

FIG. 1

FIG. 2

FIG. 3

Fig. 1 is a side elevational view of an animated rocking seat, showing my new design, the opposite side being substantially a mirror image thereof;

Fig. 2 is a top plan view; and

Fig. 3 is a front elevational view thereof.

I claim:

The ornamental design for an animated rocking seat, as shown and described.
